TOY-SIZE TESTING GAUGE

Jack G. McAllister, 2701 N. Douglass Drive,
Minneapolis, Minn. 55422

Filed June 4, 1973, Ser. No. 366,658

Term of patent 14 years

Int. Cl. D10—05

U.S. Cl. D10—64

FIG. 2

FIG. 1

FIG. 4

FIG. 3

FIG. 1 is a right side elevational view of a toy size testing gauge showing my new design, the left side being a mirror image thereto;

FIG. 2 is a top plan view thereof;

FIG. 3 is a front elevational view thereof;

FIG. 4 is a rear elevational view thereof.

I claim:

The ornamental design for a toy-size testing gauge, substantially as shown and described.
